UNITED STATES PATENT OFFICE.

SAMUEL WARRICK, OF BATTLE CREEK, MICHIGAN.

INTERLOCKING-MACHINE FOR SIGNALS AND SWITCHES ON RAILROADS.

SPECIFICATION forming part of Letters Patent No. 297,885, dated April 29, 1884.

Application filed October 15, 1883. (No model.)

To all whom it may concern:

Be it known that I, SAMUEL WARRICK, a subject of the Queen of Great Britain, residing at the city of Battle Creek, in the county of Calhoun and State of Michigan, have invented a new and useful Interlocking-Machine for Signals and Switches used on Railroads and Railways, of which the following is a specification.

10 My invention relates to improvements in that class of interlocking-machines in which several levers work independently of each other upon a shaft, and are so arranged by suitable mechanism that not more than one 15 of said levers can be operated at the same time, all others remaining locked; and the objects of my improvements are, first, to decrease the number of working parts, and thus lessen the liability to derangement; second, to 20 simplify the construction, and thus materially reduce the cost of manufacture; third, to obtain an interlocking-machine which can be easily and cheaply applied to existing signals and switches. I attain these objects by the 25 mechanism illustrated in the accompanying drawings, in which—

Figure 1 is a front sectional elevation of the entire machine. Fig. 2 is an end elevation of the same with lock-bar lever removed. Fig. 30 3 is a vertical section of the machine without the upper portions of levers, and showing a different position of the lock-bar. Fig. 4 is a plan, and Fig. 5 an elevation, of the lock-bar, and Fig. 6 an end elevation of bracket and 35 part of signal-lever, showing lock-bar applied on the outer periphery of hubs of signal-levers.

Similar letters refer to similar parts throughout the several views.

The signal-levers a a' a'' a''' , Figs. 1 and 2, 40 having hubs b , and of which a''' , Fig. 2, forms a part, are free to turn upon a hollow shaft, c , which is stationary in brackets d . These brackets hold the entire machine in place. The collars e e' e'' are entirely separate from 45 levers a a' a'' a''' , and are secured to their places on shaft c by a set-screw or other convenient mode, recesses f being provided to receive the lower end of spring-catches g , which are attached to levers a a' a'' a''' and hold them 50 in place. A lock-bar, h , with recesses i i'' i'''

i'''' in upper edge (see also Figs. 4 and 5) is free to slide horizontally in a groove or key-way formed in shaft c and in the hubs b of the levers a a' , &c., the sliding movement being controlled by the lever j and quadrant k , Fig. 55 1. The recesses i , &c., in lock-bar h are each made the length of their corresponding hubs, b , of levers a , and are also of such depth that the remaining section of lock-bar is entirely 60 within the shaft c , and therefore offers no impediment to the levers a , &c., being turned on shaft c . In Fig. 1 the spring-catch of the lever j is set in notch (marked o) of quadrant k . This, as will be observed, locks all the signal-levers, as some portion of the full section of 65 lock-bar h is within the groove of every hub b of levers a .

The mode of operation is as follows: To move signal-lever a , (also marked 1,) first move lever j into quadrant-notch 1. This will 70 bring lock-bar h into the position shown in Fig. 3, with the recess i exactly within the hub b of lever a . This leaves lever a free to turn upon shaft c when its spring-catch is released from collar e , as no portion of the lock-bar h is within the groove of hub b of lever a , (see Fig. 3,) but the remaining levers a' a'' a''' are still locked, as some portion of the full section of lock-bar h is within the groove of each of the remaining hubs b . I will now 75 presume that the lever a has been moved in the direction of the arrow, Fig. 2, to operate the signal. The levers a' a'' a''' must remain locked until lever a is returned to its original position, as the lock-bar h cannot be moved 80 until the groove in hub b of lever a is brought into position for full section of lock-bar h to enter.

The above description applies to the operation of any other of the signal-levers. The 90 numbers below notches of quadrant k correspond with those on signal-levers a . Thus, if signal-lever a' (marked 2) is to be moved, first place lever j into quadrant-notch 2. The lever a''' , Fig. 2, operates the signal or switch 95 by means of a wire rope, l , or by any other usual mode.

Although preferring to use the lock-bar h , as above described, I may use it on the outer periphery of the hubs b by providing a groove 100

any other support or its equivalent thereon, and making suitable provision on brackets *d*, or otherwise, to hold lock-bar *h* in place. (See Fig. 6, which illustrates this arrangement.) I may place lock-bar *h* at any angle, not being restricted to the vertical position in Fig. 2, or the horizontal, as Fig. 6. I may use any required number of signal-levers *a*. I am aware that prior to my invention interlocking-machines have been made with outside locking-bars operated by the spring catches of levers *a*, and locking said levers *a* indirectly through the agency of specially-shaped arms, levers, cranks, and other devices attached to said locking-bars. I therefore do not claim such a combination; but

What I do claim as my invention, and desire to secure by Letters Patent, is—

1. The combination of the signal-levers *a* 20 *a'* *a''* *a'''*, the grooved shaft *c*, and recessed lock-bar *h*, all substantially as set forth, and for the purpose specified.

2. The recessed lock-bar *h*, in combination with the hand-levers *a* *a'* *a''* *a'''*, and immediately engaging or disengaging the same, and operated solely by its own lever, and arranged either outside or inside the hub *b* of the levers, all substantially as described.

SAMUEL WARRICK.
